CLAIM

The ornamental design for a clock face, as shown and described.

DESCRIPTION

FIG. 1 is an isometric view of the clock face of my new design;

FIG. 2 is a front view thereof;

FIG. 3 is a rear view thereof;

FIG. 4 is a top view thereof;

FIG. 5 is a bottom view thereof;

FIG. 6 is a side view thereof, as viewed from the right side;

FIG. 7 is a side view thereof, as viewed from the left side;

and,

FIG. 8 is an isometric view of the clock face of my new design, similar to FIG. 1, but showing the hands in a different position.

The broken line showing of a clock mechanism is for illustrative purposes only and forms no part of the claimed design.
